DISPENSER FOR PAPER TOWELS

David G. Hope, Wauwatosa, Edwin A. Filipowicz, Greenfield, and Winford G. Renard and Robert B. Wiggins, Green Bay, Wis., assignors to Fort Howard Paper Company, Green Bay, Wis., a corporation of Wisconsin

Application March 18, 1955, Serial No. 35,110

Term of patent 14 years

(Cl. D4—3)

Fig. 2.

Fig. 1.

Fig. 3.

In the drawing, Fig. 1 is a front elevational view of the dispenser for paper towels, showing our new design;

Fig. 2 is an end elevational view thereof, the end opposite that shown in Fig. 2 being the same;

Fig. 3 is a bottom view.

The rear of the dispenser is plain.

The dominant features of our design reside in those portions shown in full lines.

We claim:

The ornamental design for a dispenser for paper towels, substantially as shown and described.
